LID FOR LOAD ON INDUSTRIAL PLATFORM PALLET OR THE LIKE

Ray P. Hattenbach, Borger, Tex., assignor to Phillips
Petroleum Company, Bartlesville, Okla.

Filed June 10, 1974, Ser. No. 477,855

Term of patent 14 years

Int. Cl. D9—99

U.S. Cl. D12—53

FIG. 1

FIG. 2

FIG. 3

FIG. 4

FIG. 5

FIG. 6

FIG. 7

FIG. 1 is a top plan view of a lid for load on industrial platform pallet or the like, showing my new design;

FIG. 2 is a front elevational view thereof, the rear being the same as the front shown herein;

FIG. 3 is an elevational view in cross section taken along line 3-3 of FIG. 1;

FIG. 4 is an elevational view in cross section taken along line 4-4 of FIG. 1;

FIG. 5 is a side elevational view thereof, the opposite side being the same as the side shown herein;

FIG. 6 is an elevational view in cross section taken along line 6-6 of FIG. 1; and

FIG. 7 is an elevational view in cross section taken along line 7-7 of FIG. 1.

I claim:

The ornamental design for a lid for load on industrial platform pallet or the like, as shown.
